CLOSURE

Theodore R. Gilliland, Washington, D. C.

Application March 15, 1937, Serial No. 131,037

5 Claims. (Cl. 221—60)

This invention relates to closures and more particularly to caps for sealing collapsible tubes such as toothpaste, toothpowder and other material. Although illustrated more specifically for use in combination with collapsible tubes the purposes of the invention are equally attainable with various other types of containers.

An object of the present invention is to provide a cap which may be threaded on to the neck of the container, retaining the advantages of the screw thread and which also may be hinged and swung laterally of the neck to permit the contents to be dispensed without completely releasing the cap so that the cap will not become lost.

A further object is to provide a screw threaded hinged cap having an eccentric hinge member adapted to enter a slot in the neck of the tube when the cap is swung on its hinge and hold the cap stationary and out of the way during the dispensing operation.

A further object is to provide means for assisting in the threading of the cap on to the neck when closing, making it unnecessary to ascertain the proper threading position.

A further object is to provide a device of this character which will be formed of a few strong simple durable and easily assembled parts, which will be inexpensive to manufacture, and which will not easily get out of order.

With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawing forming part of this specification,

Figure 1 is a longitudinal sectional view of a tube cap constructed in accordance with one form of the invention, in applied position.

Figure 2 is a view similar to Figure 1 but showing the cap open.

Figure 3 is a detail perspective view of the tube neck showing the tapered hinge pin and the slot underneath to receive the eccentric hinge eye of the cap.

Figure 4 is a plan view of the tube and cap shown in Figure 2.

Figure 5 is a longitudinal sectional view through the tube neck and cap and showing the cap screwed to the hinging position and about to be rocked to open position.

Figure 6 is a longitudinal sectional view of a modified form of the invention.

Figure 7 is a side elevation of the form of the invention shown in Figure 6.

Figure 8 is a plan view of the modified form of the invention with the cap swung open.

Except for a small portion of the eccentric hinge ear the hinging mechanism is concealed in the closed position of both forms of the invention.

Referring now to the drawing in which like characters of reference designate similar parts in the various views, 10 designates a collapsible tube having a threaded neck 11 to receive an interiorly threaded cap 12. The bottom of the thread in 15 the cap is grooved as shown at 13 to receive the circumferentially extending end of a tapered hinge pin 14.

The hinge pin 14 is provided with a radially disposed portion 15 adapted to fit in a slot 16 20 in the end of the neck and the pin is also provided with a downwardly bent anchoring end 17 that is snugly fitted in an opening 18 that extends longitudinally of the tube neck.

As best shown in Figure 5, the cap is provided 25 with a hinge ear 19 having an eccentrically disposed tapered opening 20 to receive the circumferentially and tapered extending end 14' of the hinge pin when the cap is unscrewed from the neck. The threads at the bottom of the cap and 30 top of the neck are terminated so that the cap is released for hinging at the same time the hinge eye and hinge pin are completely engaged and not before. A recess 21 is formed in the neck 11 underneath the circumferentially extending portion 14 of the hinge pin so that the moment the hinge is rocked upon the hinge pin the eccentrically disposed hinge ear 19 will enter the recess and, as best shown in Figure 4, 35 will engage the walls of the recess so that the cap 40 cannot escape from the hinge pin, the ear bearing against the walls of the recess with sufficient friction to hold the cap in the open position shown in Figure 2 when the cap is rocked to full 45 open position and permits the contents of the tube to be dispensed, without the cap falling into the way, even if the tube be inverted.

After each dispensing operation the cap may be manually rocked back on its hinge pin, and when the cap becomes aligned with the neck 50 the cap may be then screwed tight upon the neck without the necessity for finding the proper threading position since the threading alignment has been maintained by the pin and hinge eye. Groove 13 in the bottom of the thread of 55

the cap receives the hinge pin 14 during such advance of the cap to closed position. Arrow on top of cap shows direction of hinge.

5 The pin and hole are tapered at the same slope as the thread to allow the pin to pass into the hole and provide a snug fit during the hinging operation and to allow for the upward movement of the cap as it is turned, as well as to make it possible to hinge the cap about a horizontal 10 axis.

10 In the modified form of the invention shown in Figures 6 to 8 inclusive the pitch of the thread 22 in the neck 23 is increased so that sufficiently wide spaces 24 exist between the threads to receive the tapered pin 25 carried by the cap 26 and thus the groove 13 in the previously described 15 form of the invention may be eliminated.

15 In Figures 6, 7 and 8 the projection 30 which carries the hinge eye opening 29 is attached to the neck of the container while the pin is attached to the cap. As the cap is turned on the neck the pin passes in the clearance space provided between threads of the neck while the hinge eye projection passes in the clearance space provided between the threads of the cap. Since the pin 25 and the opening in the hinge eye 29 are both tapered at the same slope as the thread 22 the pin will pass into the opening in the extreme position and allow the cap to be swung 20 back away from the neck. The pin will fit snugly into the opening and the cap may be swung about the pin as a horizontal axis for a full 180 degrees to allow for dispensing.

20 The recess 27 is formed in the neck so that 35 the moment the cap is rocked upon the hinge the eccentrically disposed cam projection 28 or ear on the cap will enter the recess and will bear against the walls of the recess with sufficient friction to hold the cap in the open position. The threads at the bottom of the cap and the top of the neck are terminated so that the cap is released for hinging at the same time the hinge opening and hinge pin are completely engaged and not before. The threads on the side 40 of the neck may be cut away to allow the cap to be swung through the full 180 degrees to be 45 out of the way during the dispensing operation.

45 From the above description it is thought that the construction and operation of the invention 50 will be fully understood without further explanation.

55 What is claimed is:

1. A collapsible tube or other container having a neck, a cap screw threadedly engaged with the tube, a hinge pin extending circumferentially of the edge of the neck and traveling in the thread of the cap when the cap is screwed on to the neck or screwed to the hinging position, and

a hinge ear on the edge of the cap receiving the pin to permit the cap to be swung laterally of the neck when the cap is unscrewed to the hinging position.

2. A collapsible tube or other container having an exteriorly threaded neck, an interiorly threaded cap engaged on said neck, the bottom of the thread in the cap being grooved, a circumferentially extending tapered pin on the tube neck traveling in said groove when the cap is 10 screwed on to the neck or screwed to the hinging position, a hinge ear on the edge of the cap having an eccentric tapered opening adapted to receive said pin when the cap is unscrewed, and means on the neck adjacent to the pin receiving the eccentric hinge ear when the cap is rocked on the pin and holding the cap in rocked open position attached to the neck.

3. A collapsible tube or other container having an exteriorly threaded neck, a cap threaded 20 on to the neck, a hinge pin carried by the neck, an eccentric hinge ear on the edge of the cap engageable with the hinge pin when the cap is unscrewed, and a recess in the neck underneath the pin having walls adapted to receive the eccentric hinge ear and form stops to hold the cap stationary when swung to open position laterally of the neck.

4. A collapsible tube having a neck provided with threads of specific pitch, a cap threadedly 30 engaged on the neck, a hinge pin carried by the cap received in the spaces between said threads when the cap is screwed on or off, a projection extending from the neck, a hinge eye supported by said projection, said projection and said hinge 35 eye being received in spaces between threads of the cap, said hinge pin of the cap engaging said hinge eye of the neck when the cap is unscrewed to hinging position and permitting the cap to be swung laterally of the neck, and a cam projection 40 at the edge of the cap engageable in a recess at the edge of said neck to hold said cap stationary when swung laterally of said neck.

5. A collapsible tube or other container having an exteriorly threaded neck and an interiorly threaded cap engaging said neck, the one being provided with a hinge pin and the other with a hinge ear remotely disposed from the pin when the cap is screwed down on the neck, the pin and ear being relatively movable with one in 50 the path of movement of the other when the cap is unscrewed from the neck, the ear being provided with an opening entered by the pin at the time that the cap is released from the neck to provide a hinge connection between the cap and neck and permit the former being swung laterally away from the latter.

THEODORE R. GILLILAND.
